(57) **CLAIM**

The ornamental design for a mountable enclosure for a controller device, as shown and described.

DESCRIPTION

FIG. 1 is a perspective view of a mountable enclosure for a controller device showing our new design;

FIG. 2 is a front view of the mountable enclosure for a controller device with lid thereof;

FIG. 3 is a rear view of the mountable enclosure for a controller device with lid thereof;

FIG. 4 is a left view of the mountable enclosure for a controller device with lid thereof;

FIG. 5 is a right view of the mountable enclosure for a controller device with lid thereof;

FIG. 6 is a top view of the mountable enclosure for a controller device with lid thereof; and,

FIG. 7 is a bottom view of the mountable enclosure for a controller device.

The broken lines shown in the drawing illustrate portions of the mountable enclosure for a controller device that form no part of the claimed design.
